(57) **CLAIM**

The ornamental design for a mounting bracket for a firearm, as shown and described.

DESCRIPTION

FIG. 1 is an end view showing a first side of the top surface of my new design for a mounting bracket for a firearm.

FIG. 2 is a side view showing the outer surface thereof.

FIG. 3 is an end view showing a second side of the top surface thereof.

FIG. 4 is a side view showing the inner surface thereof.

FIG. 5 is a top view parallel with the bottom surface thereof.

FIG. 6 is a bottom view parallel with the bottom surface thereof.

FIG. 7 is an end view showing the first side of the bottom surface thereof.

FIG. 8 is an end view showing the second side of the bottom surface thereof.

FIG. 9 is a top view parallel with the top surface thereof; and,

FIG. 10 is a bottom view parallel with the top surface thereof.
